BUCKLE ASSEMBLY MACHINE

John A. Turini, Cranston, R. I.

Application December 19, 1946, Serial No. 717,181

1 Claim. (Cl. 29—3)

1

My present invention relates to the buckle art, and more particularly to a novel apparatus for assembling a buckle frame and roller.

The principal object of the present invention is to provide means for the continuous and automatic assembly of buckle frames and rollers.

Another object of the present invention is to provide an apparatus for speedily and efficiently performing in one automatic operation, several manual operations.

A further object of the present invention is to provide an apparatus for assembling buckle frames and rollers which reduces errors, promotes uniformity, and eliminates waste of materials.

With the above and other objects and advantageous features in view, my invention consists of a novel arrangement of parts, more fully disclosed in the detailed description following, in conjunction with the accompanying drawings, and more particularly defined in the appended claim.

In the drawings:

Fig. 1 is a front elevation of an apparatus embodying my invention;

Fig. 2 is a section taken on line 2—2 of Fig. 1;

Fig. 3 is a section taken on line 3—3 of Fig. 1;

Fig. 3a is a fragmentary view of a buckle frame strip and roller;

Fig. 4 is an enlarged section taken on line 4—4 of Fig. 1; and

Fig. 5 is an enlarged detailed view of the roller closing punches.

Shoe buckles and similar types of buckles are usually made by first cutting the buckle frame from sheet stock, attaching the roller and tongue to the frame by hand or on a foot press, and then finishing the buckle. These operations require the separate manufacture and individual handling of the various parts.

In my copending application entitled Method of making buckles, filed September 16, 1946, Serial No. 697,261, I have described a novel method of manufacture which eliminates the individual and excessive handling of parts by attaching the buckle parts to a continuous strip of metal prior to cutting out the blank. In my copending application entitled Buckle assembling device, filed November 8, 1946, Serial No. 708,678, I have described an apparatus for automatically and continuously forming the tongue and attaching it to the metal strip. The present invention provides

a means for automatically and continuously forming the roller and attaching it to the metal strip.

The apparatus shown in the drawings may be operated in any well known manner. However, it is preferable to attach it to and operate it by a conventional power press (not shown).

As described in my copending applications, a metallic strip is first run through a stamping press which cuts out successive openings with cross bars. Successive automatic operations attach the roller and tongue and cut the finished buckle from the strip. The present invention describes an apparatus for attaching the roller to the strip.

15 As shown in Fig. 3a, the strip 10 has been pierced to form an intermediate bar 11 to which a tongue is later attached, and a lower bar 12 to which a roller 13 is attached by the present apparatus. Mounted on the base 14 of a conventional power press (not shown), are spaced supports 15 bearing horizontal members 16 and 17 which form a channel passageway along which the metallic strip 10 is fed intermittently, Fig. 1. The intermittent feed is accomplished by a vertical shaft 18 attached to and reciprocated by the power press. A finger feed 19 is loosely pivoted at the lower end of the shaft 18, the finger portion extending into the openings in the strip 10. The rear end of the feed 19 is held upwardly by a spring 20 forcing the finger end downwardly at all times. At each downward stroke of the shaft 18, the finger 19 will kick forwardly (to the right in Fig. 1), moving the strip 10 along its channel. When the shaft 18 lifts, the spring 20 will cause the finger to pivot downwardly and slide back to engage the next opening in the strip.

As the strip 10 reaches the end of its channel, toward the center of the press in Fig. 1, it enters a working zone 21 where the roller is attached. 40 To keep the strip in proper alignment, the rear section 22 (Fig. 4) of the channel is loosely and slidably mounted and is urged inwardly against the edge of the strip 10 by a spring 23 extending from around a pin 24 on a post 25 mounted behind the channel on the base 14.

The roller 13 is formed and fed to the working zone 21 in alignment with the strip 10 and from the opposite direction. Referring to Figs. 1 to 3, a narrow metal strip 26 is fed from the right (Fig. 1) from a conventional reel (not

shown). A conventional roller feed 21, driven by the power press, is mounted to the right of the base 14. However, instead of the usual rollers, the feed 21 has a wheel 28 mounted adjacent the upper end and wheels 29 and 30 replacing the rollers. The wheel 28 has flat spaced portions 31 and outer flanges 32, the strip 26 passing over the flat portions 31 between the flanges 32 as shown in Fig. 2.

The strip 26 is now pulled over the wheel 29 which has side flanges 33, spaced portions 34 which taper inwardly, and a central U-shaped groove 35. As the strip 26 is pulled over the wheel 29 it collapses into a wide V-shape, the central portion bending into the groove 35 and 10 the side portions riding on the tapered edges 34, Fig. 2.

The strip 26 now is carried around the wheel 29 up to the lowest point where it engages the wheel 30, Fig. 3, comprises a single flat disc having a knurled edge 36 which extends into the groove 35 on the wheel 29. The wheel 30 forces the V-shaped strip 26 into the groove 35 to form an inverted U-shape, Fig. 3, which it pushes laterally toward the zone 21. Since the driving power is applied to the wheel 30 (which pulls the strip 26 through the aforementioned path), the knurled edge 36 prevents slipping and insures a uniform feed.

The inverted U-shaped strip 26 is pushed along a horizontal support 37 supported on spaced vertical supports 38. The support 37 has spaced guide blocks 39 between which the strip 26 is guided toward the working zone 21. As the forward end of the strip 26 enters the zone 21 it slides under a leaf spring 40, Fig. 4, which retains it in position during the next operation.

Referring to Figs. 1 and 4, the power press plunger has attached to it a frame 41 in which a horizontal shaft 42 is journaled. A small circular metal-cutting saw 43 is mounted at one end of the shaft 42 outside of the frame 41. A driving pulley 44 is also mounted on the shaft 42 within the frame 41. The shaft 42 and saw 43 are driven by a high-speed electric motor 45 (removed in Fig. 1 to permit an unobstructed view) through a belt 46 driving the pulley 44. The motor 45 is mounted on a platform 47 which is hingedly supported on its inner edge on a hinge-plate 48 bolted to the base 14. The platform 47 is resiliently retained in position by a heavy spring 49 extending from a post 50 on the platform 47 to a post 51 on the base 14. This construction allows the motor 45 to swing inwardly with the movement of the saw 43.

As the power press plunger moves downwardly, the saw 43, rotating at high speed, cuts through the inverted U-shaped strip 26, cutting off a piece of sufficient length to make the roller 13. This piece is held under the spring 40 in the zone 21. On the up stroke, the feed 21 pushes the strip 26 forwardly and the front end moves under the spring 40, pushing the previously cut piece out from under the spring where it drops onto the bar 12 on the strip 10, Fig. 4.

The apparatus for closing the cut strip piece 26 to form the roller 13 is shown in Figs. 4 and 5. It comprises a plunger 52, depending from the power press plunger, and having an arcuately concave bottom edge 53 which fits over the U-bend of the cut portion of the strip 26, as shown in Fig. 5. The free edges of the strip 26 are brought together, as shown in Fig. 5, by a lower plunger 54 which thrusts upwardly simul-

5 taneously with the downward thrust of the plunger 52, the plunger 54 having an arcuate cut-out portion 55 which forces the ends together as shown in Fig. 5. The base 14 has a depending post 56 on which a rocker arm 57 is pivoted. One end of the arm 57 is pivotally attached to the lower end of a plunger 58 which extends upwardly through the base 14. An operating plunger 59, depending from the power press plunger, is mounted in alignment with the plunger 58 so that downward movement of the plunger 59 causes the plunger 58 to rock the arm 57. The other end of the arm 57 is normally retained in downward position by a spring 60 positioned between the arm 57 and the under side of the base 14 and held in position by a pin 61 extending from the base 14, Fig. 4. Adjacent this end of the arm 57, a plunger 62 rests on the arm and extends upwardly through the base 14 into the lower plunger 54. Rocking motion of the arm 57 causes the plunger 62 to reciprocate the plunger 54. To insure a perfect alignment, the plunger 54 is slidably mounted in a surrounding housing or base 63 mounted on top of the base 14.

In operation, at each upward stroke of the power press plunger, the finger feed 19 pushes the strip 10 a buckle width into the zone 21, and the feed 21 pushes the cut end of the strip 26 onto the bar 12 of the strip 10. On the downward stroke, the saw 43 cuts off another piece of the strip 26, and the plungers 52 and 54 shape the roller 13 around the bar 12. This action is continuous, the strip 10, with the rollers 13 attached, leaving the device under the feed 27 (to the right in Fig. 1).

While I have described a specific embodiment of my invention, it is obvious that changes in the size, shape, and relative arrangement of parts may be made without departing from the spirit and scope of my invention as defined in the appended claim.

I claim:

In a device for applying rollers to the cross bars of buckles interconnected in the form of a strip, a base providing a working zone, a horizontal elongated guide channel mounted on said base and extending substantially to said working zone for directing said strip from one side of said base to said working zone, positive driving means for feeding said strip intermittently through said channel to said working zone, guide means mounted on said base for directing a metal strip from the other side of said base to said working zone in a direction opposite to the movement of the first said strip and to a position above the first said strip, feeding and bending means for advancing said metal strip to said working zone in inverted U-shape, a rotary saw in said working zone for severing successive lengths from said metal strip, means for applying said severed lengths to successive buckles of said strip, and a vertically movable die for bending said lengths about the cross bars of successive buckles.
